UNITED STATES PATENT OFFICE

HARRY A. YOUNG, OF CROSS PLAINS, TEXAS

FISHING TOOL

Application filed February 13, 1928. Serial No. 254,068.

This invention relates to fishing tools primarily adapted for recovering broken drill bits, underreamer, lugs or cutters, jar reins and etc.

5 An object of the invention comprehends a multiplicity of gripping elements.

Another object of the invention contemplates means adapted to expand the gripping elements when the device is called into use.

10 A further object of the invention embodies a flexible mounting for the gripping elements.

An additional object of the invention consists of twisted shanks for the gripping elements adapted to turn the latter toward its work when the tool is called into use.

More specifically stated, the gripping elements are provided with penetrating portions adapted for biting engagement with 20 the work when the gripping elements are twisted.

Frequently, an attempt to drill up or side track loose pieces of steel cause breakage of other tools and finally plug wells that may 25 have been near the pay and cost thousands of dollars to drill.

With the above and other objects in view, the invention further consists of the following novel features and details of construction, to be hereinafter more fully described, 30 illustrated in the accompanying drawings and pointed out in the appended claims.

In the drawings:

Figure 1 is an elevation of the invention. 35 Figure 2 is a fragmentary elevation showing the gripping elements shifted to an initial position to permit the insertion of work therebetween.

Figure 3 is a longitudinal sectional view 40 taken through the invention.

Figures 4, 5 and 6 are sectional views taken on lines 4—4, 5—5 and 6—6 respectively through Figure 3 of the drawings.

Figure 7 is a perspective view of a gripping element and shank therefor.

Referring to the drawings in detail, wherein like characters of reference denote corresponding parts, the reference character 10 indicates a housing having a tapered pin 50 11 upon the upper end thereof, threadedly

engaged therewith. A disk member 12, closing the bore of the housing 10, is provided with a multiplicity of rectangular shaped openings 13 and a central cylindrical opening 14 communicating with an upstanding sleeve 15. A shaft 16, having its uppermost end threadedly engaged with the tapered pin 11, is extended downwardly through the housing 10 and through the opening 14 and sleeve 15. A key 17, carried by the disk 12 55 is projected within the central opening 14, is adapted for reception within a key way slot 18 in the shaft 16.

A disk member 19, horizontally disposed within the housing 10, is in addition provided with a depending sleeve 20 having the bore thereof disposed for alignment with that of the bore 14 of the sleeve 15 to receive the shaft 16 therethrough. A stop collar 21, carried by the shaft 16, is adapted to seat the lower end of the depending sleeve 20 of the disk member 19.

A compression spring 22 encircling the shaft 16 is interposed between the underside of the tapered pin 11 and the upper side of the disk member 19 within the housing member 10 to normally repose the disk member 19 in the position as best illustrated in Figure 3 of the drawings.

Rod members 23, of rectangular cross section, are adapted for reception within openings 13 in the disk member 12. The uppermost ends of said rods are adapted for swivel connection with the disk member 19 and for this reason, the housing 10 is provided with slotted portions or portions removed, as indicated at 24, through which access may be had through the connecting ends of the rod members with the disk member 19. Said rods are twisted upon themselves to impart lateral shifting movement to gripping elements 25, carried upon the lowermost ends of the rods 23, as the latter are reciprocated within the housing.

As illustrated in Figure 3 of the drawings, the lowermost end of the shaft 16 falls short of extending the length of the rods 23, the purpose of which will be presently apparent.

Penetrating portions or teeth 26, projected 100

and curved horizontally of the gripping elements 25, are adapted for biting engagement upon its work in the manner which will be presently apparent.

5 In the use and operation of the invention, the tapered pin 11, as used on cable fishing tools, is connected to balance of fishing string (usually consisting of rope socket, stem and jars) and the tool lowered within 10 the well or well chamber.

When initially lowered within the well tubing or casing the disk member 12 is moved upwardly upon the shaft member 16 to occupy the Figure 3 position or nearly so 15 commensurate with the size or shape of the broken tool to be grasped and removed. The entire fishing string and tool is then lowered and dropped with great velocity whereby the lowermost ends of the rods 23 20 when engaging the bottom of the well about the broken tool will be shifted upwardly within the housing 10 against the tension of the compression spring 22 therein and twist upon themselves incident to the particular 25 connection between the rods themselves and the openings in the disk member 12 through which the same are slid. Consequently the rods in and of themselves will twist and cause biting engagement of the penetrating 30 elements with the broken drill bit. The disk 12 it will prevent retrograde movement of the rods even against the tension of said spring whereby the fishing string, fishing tool, and that which is recovered from the 35 well may be extracted as a unit. Such movement being effected through contact of the gripping elements engaging the broken drill bit when lowered within the well.

Upon upward movement of the tool, the 40 spring 22 will flex and compress the disk member 19 whereby the gripping elements 25 will twist and shift the teeth 26 to occupy the dotted line positions as best illustrated in Figure 6 of the drawings. The 45 teeth or penetrating elements 26 are adapted for biting engagement with the broken tool to prevent displacement or loss of the latter while being withdrawn from the well.

The invention is susceptible of various 50 changes in its form, proportions and minor details of construction, and the right is herein reserved to make such changes as properly fall within the scope of the appended claims.

55 Having described the invention, what is claimed is:—

1. A fishing tool comprising a housing provided with a sucker rod attachment upon one end, a shaft having connection with the 60 sucker rod attachment being extended from the opposite end of the housing, disks slidably mounted upon the shaft member, a compression spring encircling the shaft and interposed between the sucker rod attachment and the adjacent disk member, rods

twisted upon themselves being extended through openings in the remaining disk corresponding in shape to the cross sections thereof, the innermost ends of said rods having swivel connection with the first mentioned disk, and gripping elements carried upon the outermost ends of the rods. 70

2. A fishing tool comprising a housing provided with a sucker rod attachment upon one end, a shaft having rigid connection with the sucker rod attachment and extended through the opposed end of the housing, disk members slidably mounted upon the shaft within and without the housing, rods carried upon the innermost of the disks and projected through the outermost disk, and gripping elements carried upon the outermost ends of the rods for simultaneous rotary and reciprocating action with said rods. 75

3. A fishing tool comprising a housing provided with a sucker rod attachment upon one end, a shaft having rigid connection with the sucker rod attachment and extended for an appreciable portion of its length through the opposed end of the housing, disk members slidably mounted upon said shaft within and without the housing, rods extended through both of the disks, gripping elements carried upon the outermost ends of the rods for simultaneous rotary and reciprocating movement therewith, and a compression spring encircling said shaft for contacting engagement at its ends with the sucker rod attachment and innermost disk respectively. 80

4. A fishing tool comprising a housing provided with a sucker rod attachment upon one end, a shaft having rigid connection with the sucker rod attachment and extended for an appreciable portion of its length through the opposed end of the housing, disk members slidably mounted upon the shaft within and without the housing respectively, rods projecting through each of the disks, gripping elements carried upon the outermost ends of the rods for simultaneous rotary and reciprocating movement therewith, a compression spring encircling said shaft and interposed between the sucker rod attachment and innermost of the disks, and penetrating elements carried by the gripping elements. 85

5. A fishing tool comprising a housing provided with a sucker rod attachment upon one end, a shaft having rigid connection with the sucker rod attachment being extended for an appreciable portion of its length from the opposed end of the housing, disks slidably mounted upon the shaft within and without the housing respectively, rods having swivel and frictional engagement with the inner and outer disks respectively, said rods being twisted upon themselves beyond the innermost disk and 90

extended through the outermost disk, gripping elements carried upon the outermost ends of the rods, a compression spring encircling the shaft between the sucker rod attachment and innermost disk, and penetrating portions laterally projected from the gripping elements for biting engagement with the work.

In testimony whereof I affix my signature.
